UNITED STATES PATENT OFFICE

WARREN K. LEWIS, OF NEWTON, MASSACHUSETTS, ASSIGNOR TO STANDARD OIL DEVELOPMENT COMPANY, A CORPORATION OF DELAWARE

PROCESS OF FRACTIONATION AND APPARATUS THEREFOR

Application filed January 12, 1925. Serial No. 1,781.

This invention relates to improvements in processes and apparatus for cracking hydro-carbon oil and fractionating the resulting product. The invention will be fully understood from the following description, reference being made to the accompanying drawing, in which the single figure is a diagrammatic view of one suitable apparatus.

In the drawing, reference numeral 1 denotes cracking means arranged in a furnace setting 2. While a single coil is illustrated, it will be understood that one or more coils, pressure stills, or other suitable apparatus may be used. The stock to be treated is fed in through pipe 3. The coil 1 discharges through pipe 4 into a heat-insulated drum 5, in which further cracking takes place. A pipe 6 is arranged to take off the contents of drum 5 to separating means 7 such as a fractionating or rectifying tower. It is preferred to use a drum of the type described, but the invention is not limited in this respect.

The upper part of the separating means 7 is ordinarily designed to function as a rectifying column. It may be provided with a partial condenser, such as a coil 8, or the reflux may be obtained by returning a part of the condensate from the final condenser, or otherwise. The reflux is drawn from the tower, preferably above the point at which the cracked material is introduced. A pan 9 and draw-off pipe 10 are provided for this purpose with deflecting plates to direct the condensate from coil 8 into the pan. A bell-cap column may be used with good results. I prefer, however, to employ some type of tower filling 11 and 12, as illustrated.

The cracked product ordinarily passes in to the tower at substantially the full pressure and temperature of the cracking unit, except for the pressure drop incident to overcoming frictional resistance to flow. It is usually desirable to introduce the material into the tower at a point about one-third or one-fourth of the distance from the bottom to the top.

A stream of an aeriform fluid, preferably an inert gas or vapor, such as oxygen-free flue gas, producer gas, scrubbed still gas,

or the like, is introduced into the bottom of the tower through pipe 13 and suitable distributing means, such as a sprayhead 14. The gas or vapor strips low boiling hydrocarbons from the heavy residue or tar refluxing down the lower section 12 of the tower and collecting at its base. When an efficient tower arrangement is used, the quantity of gas required to strip the tar is relatively small.

The stripping gas or vapor may be recycled or not, as desired. In the installation shown, gasoline vapors mixed with the stripping fluid are taken off through line 15 to a condenser 16, which discharges into a container 17. The liquid product is drawn off through line 19 and part of the gas is returned to the distillation apparatus through line 20. Gas is initially introduced at 21 or other suitable location, and its pressure is maintained by pump 22. Gases generated by the cracking process are released from the drum 17 by line 21^a. Tar may be continuously or intermittently removed through line 23. The cycle stock may be received in a hot accumulator tank 24 and returned by pump 25 to coil 1 for further cracking.

A particular object of the invention is to obtain the effective removal of hydrocarbons having a low or intermediate boiling point that tend to be retained by the tar. The material discharged from drum 5 comprises vapor and liquid portions, the liquid containing dissolved vapors of naphtha and gas oil which must be stripped from the heavy tarry residue. The vapor immediately rises into section 11 while the liquid drops down on the filling material of section 12. The composition of said liquid depends on the temperature and pressure conditions. If high pressure is held in separator 7, the volatile products in the tar will not be vaporized and the remaining liquid will be lighter in gravity and will contain too large a fraction of low boiling oils to be useful as fuel oil. For this reason it has been impractical heretofore to operate fractionating towers under high pressures, since volatile products could not be effectively removed.

The function of the gas admitted to the separator through sprayhead 14 is to reduce the partial pressure of the volatile constituents in the vapors, thus allowing those fractions to distill from the heavy tar. By this means the separation is accomplished.

In view of this fact, I may operate at pressures above those at which prior hydrocarbon fractionating apparatus can ordinarily function properly. For example, I may maintain with advantage a pressure of more than 200 lbs. per sq. in., say 250 lbs. or more, on the fractionating apparatus or separator and produce a tar substantially free from naphtha or light oils which could not be obtained under the high pressure without the use of gas.

An important feature of my invention is the provision of effective countercurrent flow of the gas introduced and the tar being stripped by it. In the apparatus illustrated, this is accomplished by causing the heavy condensate to flow downwardly over the porous packing 12 placed above the spray-head 14. Merely injecting steam or gas into a body of heavy condensate will not accomplish the result desired.

The pressure in the separator 7 will ordinarily approach or equal that of the cracking system for, although the temperature in 7 is less than in 5, the gas added at 14 allows the vaporization of a large part of the material as liquid in 5. This has important advantages. For example, since the cycle stock is discharged under substantially the full pressure of the cracking unit, little expense in pumping is required for the return of this stock to coil 1. Also, its temperature is materially higher when high pressure is maintained on the distillation means.

The extent to which the light fractions are removed from the tar may be readily regulated by adjusting the amount of inert gas introduced. If the tar tends to become too viscous for easy handling, the gas stream should be reduced. The reflux through the tower may be regulated to secure the desired quality of final product. The feed stock, or other suitable liquid, may be used as the cooling means in coil 8.

While I have illustrated a system in which digestion of the oil takes place in liquid phase, the invention is not limited in this respect. The coil, drum, and condensing system may be operated in various ways in connection with the utilization of gas from an extraneous source for maintaining pressure. If desired, the invention may be applied in a unit in which a certain amount of residual cracking is allowed to take place in the tar-stripping apparatus. The fractionating column may be a part of the tar-stripping apparatus, as shown, or it may be constructed as a separate unit. Such

variations and others are included within the scope of the appended claims, in which it is my intention to claim all the novelty inherent in my invention as broadly as is permissible in view of the prior art.

70

I claim:

1. In combination, a cracking coil, a digesting chamber, a vapor separator, means for maintaining a pressure substantially above atmospheric in said separator, the separator comprising means of separating a light distillate, a heavier condensate and a tarry residue, means for circulating an aeriform fluid in effective countercurrent relation to the flow of said residue, and means for returning said heavy condensate to the cracking coil.

75

2. Process of operating hydrocarbon cracking and fractionating systems, comprising conducting the cracking and fractionating operations in separate zones under substantially the same pressure, in excess of 200 lbs. per sq. in., such pressure in the fractionating operation being in part maintained by vaporization and evolution of volatile products from the stock treated, and in part by introduction of gas into the fractionating zone, under pressure from an external source in effective countercurrent relation to unvaporized stock, condensing heavy vaporized products and separately collecting them in the fractionating zone and returning the heavy condensate to the cracking system together with the fresh feed.

80

3. Process of operating hydrocarbon cracking and fractionating systems, comprising cracking hydrocarbons under superatmospheric pressure in a cracking zone, fractionating the cracked products into tar, cycle stock and overhead distillate in a fractionating zone under superatmospheric pressure not exceeding the pressure in the cracking zone, furthering vaporization in the fractionating zone by introducing inert gas thereto in effective counter current relation to unvaporized cycle stock, and returning the cycle stock to the cracking zone for further cracking.

4. Process of operating hydrocarbon cracking and fractionating systems, comprising cracking hydrocarbons under superatmospheric pressure in a cracking zone, fractionating the cracked products into tar, cycle stock and overhead distillate in a fractionating zone under superatmospheric pressure not exceeding the pressure in the cracking zone, furthering vaporization in the fractionating zone by introducing inert gas thereto in effective counter current relation to unvaporized cycle stock, and returning the cycle stock to the cracking zone for further cracking.

105

5. Process of operating hydrocarbon cracking and fractionating systems, comprising cracking hydrocarbons under superatmospheric pressure in a cracking zone, fractionating the cracked products into tar, cycle stock and overhead distillate in a fractionating zone under superatmospheric pressure not exceeding the pressure in the cracking zone, furthering vaporization in the fractionating zone by introducing inert gas thereto in effective counter current relation to unvaporized cycle stock, and returning the cycle stock to the cracking zone for further cracking.

120

6. Process of operating hydrocarbon cracking and fractionating systems, comprising cracking hydrocarbons under superatmospheric pressure in a cracking zone, fractionating the cracked products into tar, cycle stock and overhead distillate in a fractionating zone under superatmospheric pressure not exceeding the pressure in the cracking zone, furthering vaporization in the fractionating zone by introducing inert gas thereto in effective counter current relation to unvaporized cycle stock, and returning the cycle stock to the cracking zone for further cracking.

125

7. Process of operating hydrocarbon cracking and fractionating systems, comprising cracking hydrocarbons under superatmospheric pressure in a cracking zone, fractionating the cracked products into tar, cycle stock and overhead distillate in a fractionating zone under superatmospheric pressure not exceeding the pressure in the cracking zone, furthering vaporization in the fractionating zone by introducing inert gas thereto in effective counter current relation to unvaporized cycle stock, and returning the cycle stock to the cracking zone for further cracking.
